 Attorneys.*

United States Patent Office.

DANIEL BULL, OF AMBOY, ILLINOIS.

Letters Patent No. 96,880, dated November 16, 1869.

IMPROVED CARRIAGE-JACK.

The Schedule referred to in these Letters Patent and making part of the same.

To all whom it may concern:

Be it known that I, DANIEL BULL, of Amboy, in the county of Lee, and State of Illinois, have invented a new and valuable Improvement in Lifting-Jacks; and I do hereby declare that the following is a full, clear, and exact description of the construction and operation of the same, reference being had to the annexed drawings, making a part of this specification, and to the letters and figures of reference marked thereon.

Figure 1, of the drawings, is a side view of my invention.

Figure 2 is a vertical section of the same.

Figure 3 is a detached view of the inside wall of the lever, showing recess and spring.

My invention relates to lifting-jacks; and consists mainly in the construction and novel arrangement of devices, whereby a jack of extraordinary power is produced, easily raised, automatically fastened, and readily lowered.

The letter A, of the drawings, designates the frame of the lifting-jack, made of iron, wood, or other strong material.

It consists of the bed-piece *a*, made broad to afford a good foundation, and prevent slipping, the rack-bars *A' A'*, brace *b*, and collar *C*.

D is the lifting-bar, which passes up through the collar *C*, and at its lower end is pivoted between the chucks *H K* of the operating lever *G*, by the pin *e*.

G represents the operating lever, slotted to receive the rack-bars *A' A'*.

The lever is formed of one piece, with exception of the plate *H*, forming a wall of the slot and secured to the main portion of the lever by four screws, *b' b'*.

Between the walls *H* and *K*, on each side of the lower end of the lifting-bar *D*, are pivoted, by means of the fulcrum-pins *c c*, the dogs *L L*, in such a manner that their lower ends will engage with the horizontal faces of the teeth of the rack-bars.

The lifting-bar *D*, at its lower end and on the side next the removable plate *H*, is recessed to receive a forked spring, *V*.

This spring embraces the lower end of a projecting ridge, *d*, in the lifting-bar, and, passing up on each side of this ridge, is clamped by the small lugs *i i*, and then its free ends expand upward and outward, in such a manner that when this spring *V* is pushed up to its

highest limit, its expanded ends will engage with the upper ends of the dogs *L L*, pressing them toward the rack-bars, and thus causing their lower ends alternately to clear the teeth when the lever is worked in the descending movement.

Or, if a quick descent is desired, a jerk upon the handle of the lever, either upward or downward, will cause a downward alternate movement of the dogs, which will be continued automatically, the hand being removed from the lever.

When the spring *V* is pushed down, it has no effect on the dogs *L L*, which then pass under the control of the smaller spring *s*, lying in a recess in the wall *K* of the lever, and attached to the stud *z* in the upper part of this recess.

The ends of the spring *s* expand downward and outward, and engage directly with the lower arms of the dogs *L L*, pressing them out in such a manner that their lower ends, under the working of the lever, will alternately engage with the teeth of the rack-bars. In this manner the pins *c c* become alternately the fulcrum of the lever *G*.

That this lifting-jack may be made of immense power, is evident from the short distance obtained between the fulcrum *c c* and the pin *e*, upon which the weight rests.

What I claim as my invention, and desire to secure by Letters Patent, is—

1. The reciprocating rack-bars *A' A'*, arranged on the standards to afford alternate support to the fulcrum of the lever *G* of a lifting-jack, as specified.
2. The double fulcrum-lever *G*, with its dogs *L L*, when combined with double standards having ratchets, as described, and when arranged to operate as set forth.
3. In combination with the spring *s*, lifting-bar *D*, and double fulcrum-lever *G*, having dogs *L L*, working on the rack-bars *A' A'*, the sliding spring *V*, constructed and arranged to operate as specified.

In testimony that I claim the above, I have hereunto subscribed my name, in the presence of two witnesses.

DANIEL BULL.
